CREEL BOARD CLEANER

Henry E. Griemsmann, Elmira Heights, N. Y., assignor, by mesne assignments, to Bendix Aviation Corporation, South Bend, Ind., a corporation of Delaware

Application June 15, 1939, Serial No. 279,293

3 Claims. (Cl. 57—56)

The present invention relates to a creel board cleaner for spinning frames and the like and more particularly to a mechanical cleaner of the roller type such as disclosed in the copending application of Garey, Serial Number 274,203, filed May 17, 1939.

It is an object of the present invention to provide a novel creel board cleaner which is simple and economical in construction and reliable in operation over long periods of use.

It is another object to provide such a device which embodies a novel operating mechanism for actuating the cleaner from the drive mechanism of the spinning frame.

It is another object to provide such a device in which the operating mechanism is easily installed on spinning frames without removal or alteration of the creel boards and with a minimum interruption of the operation of the frame.

It is a further object to provide such a device in which the operating mechanism is readily adaptable to any size or type of spinning frame without the necessity of special fittings or design.

Further objects and advantages will be apparent from the following description taken in connection with the accompanying drawings in which:

Fig. 1 is a vertical sectional view of a portion of a spinning frame showing the installation thereon of a preferred embodiment of the present invention;

Fig. 2 is an end elevation of such a spinning frame showing a preferred embodiment of operating means for the creel board cleaner;

Fig. 3 is a side elevation of a portion of a spinning frame showing the creel board cleaner and operating mechanism therefor;

Fig. 4 is an enlarged detail of the reversible gear drive for the operating mechanism, partly in elevation and partly broken away; and

Fig. 5 is a detail in perspective of a cleaning device with a novel form of protective cover installed thereon.

In Fig. 1 of the drawings there is illustrated a spinning frame comprising a support 1, a lower creel board 2 mounted thereon, and an upper creel board 3 supported by means of pedestals 4 and brackets 5. Bobbins 6 are pendulously supported from the upper creel board 3 in spaced relation to the lower creel board 2, and the rovings therefrom are arranged to pass through spinning and drawing roller assemblies 7 from which the yarn is wound on receiving bobbins 8.

It will be understood that there may be a plurality of superimposed creel boards and sets of bobbins, and an upper bobbin assembly is indicated in Figs. 1 and 3, but since such parts are a duplication of those already described, further description thereof is deemed unnecessary.

According to the present invention, a rolling collector 9 of dirt, lint and other deposited material is provided for the purpose of maintaining the creel boards clean and preventing the formation of slubs or other imperfections in the yarn due to the adhesion of such material to the yarn as a result of circulation in the air by blowers or other agitating means.

Such a rolling collector is disclosed in the application of Garey above referred to, and the present invention concerns more particularly novel actuating mechanism therefor.

As here shown, the roller comprises a cylindrical member 11 of any suitable heavy material having an affinity for lint and dust such as iron having a covering 12 (Fig. 5) of felt or similar material. A groove 13 is formed centrally in the roller, and guide rails 14 are mounted on the creel board 2 running from end to end thereof and arranged to enter the groove 13 in the cleaner and guide its progress from end to end of the creel board.

Flexible operating means for the cleaner is provided in the form of a link belt or chain 15 (Figs. 2 and 3), which belt runs between the rails 14. The rails 14 are mounted as shown in parallel relation, separated by a slit, and a fork member 16 (Fig. 5) fixed on the belt 15 is arranged to project through the slit and embrace the axle 17 of the cleaner. The transmission member 15 is preferably formed as an endless belt, traversing adjacent creel boards, and may thus be used to operate cleaners on two superimposed creel boards as illustrated, the cleaners being arranged to travel in opposite directions on the two creel boards.

Means for causing the transmission element 15 to reverse its travel when the cleaners reach the end of the creel boards to cause the cleaners to reciprocate over the creel boards, is provided in the form of reversible gearing driven from a suitable element of the spinning mechanism.

As here illustrated, a belt or chain 18 (Fig. 3) operated from any suitable rotating part of the spinning mechanism is caused to rotate a shaft 19 on which is mounted a pulley 21. A second pulley 22 is connected by a belt 23 to the pulley 21 and drives a shaft 24 (Fig. 4). Shaft 24 car-

ries a bevel gear 25 fixed thereon, which meshes with a pair of bevel gears 26 and 27 swiveled on a cross shaft 28. A wheel or sprocket 30 (Fig. 3) is mounted on the end of shaft 28 in position to engage the actuate the belt 15. In case a plurality of cleaners for each creel board is employed, a corresponding plurality of sprockets 30 will be provided as indicated in Fig. 2. Means for selectively keying the bevel gears 26 and 27 to shaft 28 is provided in the form of a clutch member 29 splined to shaft 28 and movable to engage corresponding clutch elements on gears 26 and 27 by means of a fork 31 slidably mounted in a casing 32 in which the shafts 24 and 28 are journalled.

15 A lever 33 is pivoted in the casing 32 and is arranged to engage and operate the fork 31 under control of a snap-action shifter here shown as a shifting element 34 pivoted at 35 to an extension of the casing 32 and actuated by a spring 36 to bring one or the other of its arms 37 or 38 into engagement with the free end 39 of lever 33. An actuating arm 41 for the shifter 34 is provided having a terminal loop 42 surrounding the belt 15. A projection 43 (Figs. 2 and 3) fixed to the belt 15 is arranged to engage the actuating arm 41 when the cleaner has reached the end of the creel board whereby the shifter 34 is swung in a direction to cause actuation of the clutch member 29 to reverse the gearing and thereby cause 30 retrograde motion of the belt. It will be understood that the projection 43 on the belt is of such dimensions as to enable it to slide between the guide rails 14.

In operation, actuation of the mechanism of the spinning frame causes the belt pulley 22 and shaft 24 to constantly rotate at low speed. This rotation is transmitted through the bevel gearing to the shaft 28 and through the sprocket 30 to the belt 15. The consequent motion of belt 15 causes 35 the cleaner 9 to roll over the surface of the creel board to pick up any foreign material deposited thereon. When the cleaner reaches the end of the creel board, a projection 43 engages the actuating arm 41, causing the gearing to be reversed, 40 which continues until the cleaner reaches the opposite end of the creel board, whereupon a second projection 43 engages the actuating arm 41 to again cause reversal of the gearing.

From time to time the operator removes the 50 material which is collected and wound up on the cleaner by raising the cleaner and sliding the collected material endwise therefrom.

In some cases it has been found desirable to provide the cleaner with a cover or guard to prevent 55 a broken roving or the like from engaging and adhering to the cleaner. One preferred form of such guard is illustrated in Fig. 5 in the form of a generally semi-cylindrical sheet metal shield

44 fixed as by means of screws 45 to a block 46 journalled on the axle 17 of the cleaner.

Although but one embodiment of the invention has been shown and described in detail, it will be understood that other embodiments are possible and various changes may be made in the design and arrangement of the parts without departing from the spirit of the invention as defined in the claims appended hereto.

What is claimed is:

1. In combination with a spinning frame including upper and lower creel boards and a plurality of bobbins suspended from the upper creel board, means for maintaining the lower creel board free from deposited material including a cylinder having a felt-like covering, means including a reversible belt for rolling the cylinder from end to end of the creel board, and a shield for the roller journalled thereon having a smooth exterior surface to prevent the attachment of 20 broken ends to the roller.

2. In a spinning frame, a creel board, bobbins pendulously suspended above the creel board, a hollow guide member mounted on the surface of the creel board, a cylinder adapted to roll on the 25 surface of the creel board having a lint-collecting surface and a circumferential groove in its mid-portion, said groove being arranged to loosely embrace the guide member, a flexible traction element traversing the interior of the guide member, 30 a fork on the traction element adapted to engage in the groove of the cylinder, and means for actuating the traction element including reversible gearing, a shift lever for the gearing and a projection on the traction element arranged to 35 traverse the guide member and adapted to engage and actuate the lever to reverse the gearing.

3. In a spinning frame, superimposed creel boards, bobbins pendulously suspended above the creel boards, hollow guide members mounted on 40 the surfaces of the creel boards, cylinders adapted to roll on the surfaces of the creel boards having lint-collecting surfaces and circumferential grooves in their mid-portions, said grooves being arranged to loosely embrace the guide members, 45 a flexible traction element traversing the interior of the guide members, forks on the traction element adapted to engage in the grooves of the cylinders, means for actuating the traction element including reversible gearing, a shift lever 50 for the gearing provided with an opening adapted to be traversed by the traction element, and a pair of projections on the traction element arranged to traverse the guide members and adapted to engage and actuate the lever to reverse the gearing.

HENRY E. GRIEMSMANN.
